United States Patent Office.

WILLIAM SYKES, OF SHEFFIELD, ENGLAND.

Letters Patent No. 99,493, dated February 1, 1870.

IMPROVEMENT IN TUNNELLING RIVERS.

The Schedule referred to in these Letters Patent and making part of the same.

I, WILLIAM SYKES, of Sheffield, in the county of York, England, have invented a new and useful Method of Tunnelling under Rivers, &c.

Nature and Objects of the Invention.

My invention is applicable to the construction of tunnels, of whatever description, under rivers and other shallow bodies of water having alluvial beds.

The improvement consists in the employment or use of an isolating-shield in which to perform the work of excavation and building, and to form further, preferably, wholly or in part, a sheathing for the finished tunnel, said shield being adapted to be built at convenient places, floated in sections to the desired locality, and sunk.

Description of Drawings.

The accompanying drawings, illustrating my improved method of tunnelling, represent its application to the construction of a double brick tunnel.

Figure 1 being a transverse section of the finished tunnel.

Figure 2, a transverse section of the shield in position and ready for the commencement of the building.

Figures 3 and 4, horizontal sections, in different planes and on a contracted scale, of the shield, as represented in fig. 2.

Figures 5 and 6, longitudinal sections on the same scale as figs. 3 and 4, respectively, representing the shield as represented in said figures and fig. 2, and the tunnel completed, as represented in fig. 1.

The dotted lines *z y*, in fig. 5, indicate the planes of the horizontal sections, figs. 3 and 4, respectively.

General Description.

The isolating-shield, forming the essential feature of my invention, indicated by *A* in the drawings, is a bottomless structure corresponding in transverse form and dimensions with the particular tunnel, in the building of which it is employed. In length, it may be adapted to extend the whole or any desired portion of the distance across the body of the water. It is of such depth as to project slightly below the foundation of the tunnel proper, as shown.

It is built in sections, 1 2, of proper length to enable its construction at convenient points, and transportation to the place where it is to be used, and to facilitate its use.

Its sides are supported laterally at their lower edges by a "grid" or frame, *a*, and the marginal bars *b* of this grid or frame are sharpened and hardened, to enable them to cut into the bottom when the shield is sunk thereon.

At suitable intervals, preferably, for convenience, at the ends of the sections, turrets *e*, wholly or in part

removable, are provided to give access to its interior during the operations of excavating and building, said turrets being of such height as to enable them to project a safe distance above the surface of the water when the shield is at the desired level.

The respective sections are adapted severally to receive chambers or tanks, *d*, or their equivalent, in their upper part, and suitable temporary framing, *c*, for the support of such chambers, and also temporary water-tight ends *f*, with all of which they are preliminarily provided, to enable them to be floated to the desired locality and sunk, the chambers or tanks *d* serving, in an empty condition, as buoys for floating the sections, and when filled with water, or other material, or both water and other material, to admit of which they are provided with sluices, *d'*, or suitable plugs, as weights to sink or aid in sinking them, and the ends *f* serving to close the individual sections prior to their connection, to enable the extraction of water to permit the descent of workmen, &c., for performing the work of excavation.

After being sunk, the sections are connected by sheet-piling, *B B*, which, with the removable parts of the shield proper, are taken away on the completion of the tunnel, or as they may be dispensed with.

g, in the drawings, represents a boiler-plate tie and a filling, to prevent the water settling between the two ridges of the form of tunnel shown, and to keep the structure firmly together.

When employed, it is applied in the original manufacture of the shield, and only by having chance for application, thus is enabled to be used.

I propose employing any suitable material or combination of different materials in the construction of the body of the shield. As represented, it is built of plate-iron, strengthened by internal *T* and *L*-ribs.

The details of construction will vary with particular circumstances, and the material employed. The precise details of operation may also be varied to suit particular circumstances.

Removable floors may, in connection with the temporary ends *f*, or inner doors, form the chambers for floating and sinking in the sections, and the separate chambers *d* be dispensed with, or any other equivalent of said chambers may be employed.

The turrets may be adjustable in height, to enable them to be extended as required, and are in any case removable at about the bed of the river, being connected at this point by bolts and nuts, or similar fastenings.

Mode of Operation.

The proposed mode of building, transporting, sinking, and using the shield is as follows:

The character and dimensions of the desired tunnel

being determined, the shield is built, in sections as stated, of the preferred material or materials.

The building is performed in suitable docks, near the proposed site of the work. Each section is here fitted up complete with the chambers *d*, or the equivalent thereof employed, with the turrets *c*, or the permanent portions of them, and with the temporary ends *f*. On the completion, when it is required, water is admitted to the dock, floating the section, when it may be towed to the site.

Reaching the site, the section is placed in position, and secured there by temporary piling, barges, or other suitable means. At the proper moment, the sluices *d* in the chambers *d* are opened, and the water permitted to fill them, (other weighty material being added, if desired,) sinking the section. The chambers are then closed, so as to retain the water in them. On the grid *a* being found to have cut a sufficient distance into the material of the bed, which may be assisted or accelerated by exhausting the air from the turrets by suitable means, the water is pumped out of the lower portion, and workmen sent down to take out the excavation.

The weight of the section itself, increased by the water in its elevated chamber, will usually be sufficient to gradually sink the section. Should, however, the surface-friction prove too great to prevent it readily sinking, the air may again be exhausted to afford the requisite additional pressure.

The excavated material is hoisted through the turrets, and removed by barges.

In case of quicksand occurring in the excavation, and occasioning trouble, an air-lock may be made in each of the turrets, and by means of an air-pump the atmosphere in the interior of the section so compressed as to overcome the influx of water and sand, when the men can continue to work, sending out the excavated material through the air-locks.

When the necessary depth is reached, the work of excavation is stopped, and that of laying the masonry, indicated by *C* in the drawings, commenced. Should the ground require it, the bottom is first covered to a proper depth with a bed of concrete, as indicated at *D* in the drawings, for security; but if the bottom is found to be of hard and strong material, the concrete need only be used for the purpose of giving form for setting the masonry.

The building-materials may be introduced through the turrets, or through the finished end of the tunnel, or both.

The chambers *d* are emptied, and, with their sup-

ports *i*, are removed as the mason-work progresses, being taken out through the turrets.

For the withdrawal of the water from the chambers *d*, any suitable means may be employed.

On one section being sunk to its place, or during the operation of sinking it, another may be brought into line, and as nearly as possible to it, and sunk in the same manner as the first.

On both reaching the desired level, they are connected by the piling *B*, as indicated in figs. 3, 4, 5, and 6, the water in the enclosure thus made pumped out, and excavation made to the depth of the tunnel, when the temporary ends or doors *f* being removed, the masonry may be continued from one section of the shield to the other.

The masonry at these points, including the width of the turrets, is covered with boiler-plate. The body of the shield forms a permanent covering for it at other points, the ribs, &c., of said shield, when internal, being embedded in the same, as indicated in the drawings.

The tunnel being completed, the turrets *c* are removed at the surface of the bed, and the piling *B* drawn, when the bed is left perfectly clear.

It will be seen from the above that I am enabled by my invention to utilize the water, under which the tunnel is to be constructed, for transportation, &c., to make the necessary excavation, and build the tunnel with minimum amount of labor, and greatest possible speed, with less danger than by the old methods, at the same time producing a superior tunnel, and not in the least impairing navigation, and with a less depth of excavation adjoining thereto.

Claims.

I claim, as my invention—

1. The method of constructing subaqueous tunnels, by means of a shield, adapted to be floated and sunk into its proper position, and to receive a lining of masonry, substantially as set forth.
2. The shields or sections 1, 2, constructed with open bottom and ends, and provided with penetrating grids *a*, *b*, turrets *c*, elevated chambers *d*, and removable ends *f*, substantially as described, for the purpose set forth.

WILLM. SYKES.
